UNITED STATES PATENT OFFICE

WILLIAM G. VENARD, OF LONG BEACH, CALIFORNIA

ADJUSTABLE SKIP HOIST

Application filed April 9, 1928. Serial No. 268,729.

This invention relates to contractors' equipment and more especially to hoist skips and their scaffolds.

An object of this invention is to provide a scaffold of sectional form whose parts may be readily set up and later dismantled for repeated re-use, and to provide a scaffold apparatus having an adjustable top or unloading deck.

10 A further object is to provide a skip scaffold and a skip operative therein and of adjustable form so as to vary capacity and be adaptable as a platform for carrying loads of construction material and for arrangement 15 horizontally as an elevator for wheeled vehicles.

Numerous additional objects, advantages and features of construction and arrangement, and details of means will be made manifest in the ensuing description of the here-with illustrative embodiment; it being understood that modifications, variations and adaptations may be resorted to within the spirit, scope and principle of the invention 25 as it is hereinafter more directly claimed.

Figure 1 is a front elevation of the upper portion of the scaffold and its top deck, and the hoisting skip. Figure 2 is a plan of a bracket spider. Figure 3 is a detail view of 30 the joint of a pair of deck sections. Figure 4 is a sectional perspective of a deck girder member and its dowel pin. Figure 5 is a horizontal section of a stationary skip guide and a skip shoe therein. Figure 6 is a top plan 35 of a part of the hoist skip and an end extension thereof, and of scaffold means. Figure 7 is an elevation of one of the scaffold standards. Figure 8 is a plan of a foot-iron of a standard. Figure 9 is a plan of a cross-tie 40 and a crows-nest rest therefor on a standard.

Figure 10 is a plan of a header extension of the scaffold. Figure 11 is an elevation of an erected sectional standard; showing spaced crows-nest. Figure 12 is an elevation of an 45 erected skip guide. Figure 13 is a perspective of a skip guide unit section. Figure 14 is an elevation of a topping-off standard unit section and its crows-nest. Figure 15 is a plan of a crows-nest on its standard unit. 50 Figure 16 is a side elevation and vertical sec-

tion of the scaffold; showing the skip arranged horizontally. Figure 17 is a detail section of a skip beam and extension mount. Figure 18 is a perspective showing an arrangement of the top platform leaf and an 55 end section thereof. Figure 19 is a side elevation of the scaffold and its top deck arranged as a dump-way; the skip being adjusted for bulk load lift and discharge. Figure 20 is a detail showing an adjustable connection for the skip joist 15. 60

The invention includes a scaffold structure comprising a rear pair of spaced and connected poles or standards S and a pair of spaced guides G; the latter being spaced less 65 than and in advance of the former, Fig. 8, and forming runways for a vertically movable skip or hoist H.

In Fig. 11 the standard is shown as including a number of tubular sections 2, and, if 70 needed, subsections 3, all having rigid brackets or crows-nests 4 at suitable pitch, and also having, on their lower ends, fixed sockets 5 to receive abutted sections of the standard as erected.

75 The vertical guides G each include a series of superimposed, channel-iron sections 6 and subsections 7, the former having joint sockets 8 fixed on their upper ends for added subsections 7 which may have sockets 8 on either 80 end or none so that a proper length of guide may be set up to a coordinate standard S.

The guide sections (including the shorter subsections) have the side walls of the channels converged as clearly shown in Fig. 5, 85 and the erected guide parts form a smooth runway for the shoes or runners 10 attached to skip frame parts 11 which are upright and transversely connected by top and bottom bars 12-13. On the top bar 12 is pivoted 90 at 14 a set of inverted channel joists 15 on the top of which is laid a floor 17 constituting the main bed of the skip and on this may be laid guard beams 18.

95 For the purpose of increasing the floor areas of the skip end floors 19 on bed frames 20 are bolted at 21 against the end beams 14 and are braced by braces 22-22^a whose lower ends are stepped on brackets 23 attached to the side pieces 11 of the skip frame. The 100

skip floor means is adapted to be set at various angles to the vertical frame and this is provided for by adjustable braces 24 whose lower ends are hinged at 25 to the bottom bar 13 of hoist frame; the braces 22^a also being 5 extensible.

When desired a front extension floor 26 is hung in the channel joists 15 by means of horns 27 sliding thereinto and resting on 10 loops 28 to which the braces 24 are attached.

The hoist is provided with an apron 29 hinged to be thrown over the top of its guides G when the hoist is used for elevating bulk material, as lumber, lath and other structural 15 parts.

The front guides G and the rear standards S are connected by foot irons 31, Fig. 8, and also by transverse tie-bars 32, Fig. 9, which have angle-iron arms 33 Fig. 7, with dowel 20 pins 34 to set in pin holes 35 in the flange or top body of the crows-nest.

On the forward ends of the brace arms 33 are sockets 36 to embrace contiguous sections or units 6—7 of the guides G, thus staying 25 them in vertical position and proper gage for the skip runners.

The arms 33 of the scaffold have thrust bars 33^a adjustable to abut the near wall W in relation to which the scaffold is set up and 30 vertically heightened section by section as the wall is laid.

Material elevated or vehicles (wheel-barrows) may be put off the hoist at any level or carried to the top of the scaffold and dumped or run onto a top deck structure which is carried by a top girder or header including a pair of L-irons 40 fixed in spaced relation on the crown-irons 30 and receiving slip hinge 35 leaves 41 pivoted at 42 in the ends of sets of deck joists 43 which are inverted channel irons. On these are fixed transverse joists 44 having out-turned webs 45 on which is secured a suitable floor 46 which may have 40 protective guard strips 47 to receive the shock 45 or heavy building iron or lumber dumped off the skip.

Hanging from the joists 43 are links 48 and these carry brace spiders 48' on which are pivoted adjustable braces 49 whose outer ends are connected to straps 50 on the outer edge 50 of the main deck 46. A swinging leaf deck 51 is hinged at 52 to the main deck 46 and has projecting horns 53 to bolt solidly to the girders 43 when the decks 46—51 are hung in a common plane, as in Fig. 19, to form a dump-way over a building floor F.

The scaffold header 40 may be increased in length by addition of header extensions 40^a 60 having hook-plates 40^b to interlock on bolts 40^c in the main header. Extension decks 46^a are laid on the ends 40^a.

As clearly shown in Figs. 3 and 4, the decks 46—46^a have dowel pins 55 to drop into 65 respective holes 56 provided in subjacent gird-

ers 43—43^a when these are hinged at 42 to the header elements.

The end or extension decks 46^a have hooks 57, Fig. 18, to be applied, at will, to the end girders of deck 51 which have slots 58 for the 70 hooks. Thus the end decks may be installed either on the ends of the main decks or on the ends of the leaf 51 as run-ways therefrom.

In Figure 16 the decks and the skip are set for service of wheel-barrows and the like.

The deck braces 49 are radial to the spiders 48, as seen in Fig. 1.

Any appropriate hoisting rig and tackle 60 may be employed to run the skip.

The top deck has pivoted, adjustable legs 61 and 62 to be dropped into place in the building structure as may be needed in various uses of the apparatus.

Fig. 20 shows the skip floor members 15 as adjustably bolted to a hinged section 15^a 85 allowing the floor to be adjusted outwardly so that the apron 29 can be swung down flat.

What is claimed is:

1. A skip hoist and scaffold apparatus including a standard and guide structure including a header means, and an unloading deck adjustably connected to the header means.

2. A skip hoist and scaffold apparatus including a standard and guide structure including a header means supported thereby, and an unloading deck adjustably connected to the header means; said unloading deck including a main part and extension end sections having braces supported by said structure.

3. A skip hoist and scaffold apparatus including a header supported by standards, and an unloading deck adjustably connected to the header; said unloading deck including a main part pivoted on the header and a leaf part hinged thereto along one edge and supporting props for the leaf part.

4. A skip hoist and scaffold apparatus including a header means having standards, and an unloading deck adjustably connected to the header means; said unloading deck including a main part; and adjustable brace means between the standards and the main section.

5. A skip hoist and scaffold apparatus including a header supported by standards, and an unloading deck adjustably connected to the header; said unloading deck including a main part and a leaf part hinged thereto along one edge; and means for securing the leaf in the plane of the main section.

6. A skip hoist and scaffold apparatus including a header, and an unloading deck adjustably connected to the header; said deck having hinge leaves for slip connection to and from the header to facilitate mounting and dismounting.

7. A skip hoist and scaffold apparatus including a header, and an unloading deck ad-

justably connected to the header; said unloading deck including a main part and extension end sections, and a leaf section; said end sections being connectible to the leaf section to form run-ways.

5 8. A skip hoist and scaffold apparatus, including a header, and an unloading deck adjustably connected to the header; said header including spaced members forming a slot, and the deck having hinged leaves to be dropped in the slot to connect the parts.

10 9. In a skip hoist apparatus, a skip having a vertical frame, upright, running shoes on its ends, a platform hinged to the top of the frame, adjustable means to support the platform at various angles, end extension platforms attachable to the main platform and adjustable therewith and having oblique corner braces converging to and having bottom rests on the lower part of the frame.
